John L. Rone

UNITED STATES PATENT OFFICE.

JOHN L. ROWE, OF NEW YORK, N. Y., ASSIGNOR TO HIMSELF AND T. RUDDERFORTH, OF SAME PLACE.

ICE-CRUSHER.

Specification of Letters Patent No. 31,766, dated March 19, 1861.

To all whom it may concern:

Be it known that I, JOHN L. ROWE, of the city and State of New York, have invented, made, and applied to use a certain new and useful Improvement in Ice-Crushers; and I do hereby declare that the following is a full, clear, and exact description of the construction and operation of the same, reference being had to the annexed drawing, 10 making part of this specification, wherein I have represented a vertical section of my said invention.

For soda water, lemonade and other liquids drank in summer time particularly, 15 it is necessary to introduce ice to render them palatable. It is now usual to crack a lump of ice up into small pieces by striking the same while held in the hand, this operation is unpleasant because of the cold 20 and wetness to the hand, and beside this the ice is not sufficiently comminuted to act quickly in cooling the liquid into which it is introduced.

My said invention is intended to crack 25 or grind up pieces of ice sufficiently small for the foregoing purposes and consists in a fluted roller applied in a hopper, one side of which is movable, the parts acting in such a manner that upon revolving the fluted 30 roller the ice is crushed and broken into small pieces adapted to use in soda water, lemonade, beer &c.; or the ice thus crushed up may be applied in ice cream freezers or under any similar circumstances.

35 In the drawing *a*, is a fluted roller the axes of which are sustained in the end pieces of the hopper *b*, and said hopper may be sustained upon legs *c*, so that a tumbler or other receptacle for the ice may 40 be placed beneath. The roller *a*, is fluted lengthwise and the side *d*, of the hopper is to be fluted vertically and at right angles or nearly so to the flutes on *a*. The side *d*,

is to be attached to the end pieces of the hopper by gudgeons near the upper corners, 45 so that the lower side can be brought nearer to or farther from the fluted roller *a*, to regulate the size of the lumps of ice and a pawl or button *e*, at each end of the hopper sustains the side *d*, at the required position. 50 The roller *a*, may be revolved by a crank applied to one of the journals. I have however shown a gear wheel *f* at one end of the roller and the pinion *g* taking the same, and to the shaft of this pinion the crank arm 55 is to be applied as shown by dotted lines. The hopper (*b*), may be provided with a hinged cover *h*, if desired.

The benefits derived from this arrangement and the convenience afforded will be 60 apparent. The ice is crushed and broken without loss, and under circumstances adapted to the use of hotel keepers, in restaurants, &c.

It will be evident that the grooves in the 65 side *d*, running vertically, act to crack the ice into small lumps as carried through by the projections on the cylinder or roller *a*, whereas the ice would be ground up and detained in the grooves, at considerable loss, 70 if the grooves in the side *d*, run parallel to the roller *a*.

What I claim and desire to secure by Letters Patent is—

The adjustable side *d*, grooved vertically 75 as specified in combination with the roller *a*, to crack and break ice in the manner specified.

In witness whereof I have hereunto set my signature this sixteenth day of February 1861.

JOHN L. ROWE.
